(57) **CLAIM**

The ornamental design for a vehicle mount, as shown and described.

DESCRIPTION

FIG. 1 is a perspective view of a vehicle mount;
FIG. 2 is a front view of the vehicle mount of FIG. 1;
FIG. 3 is a rear view of the vehicle mount of FIG. 1;
FIG. 4 is a left-side view of the vehicle mount of FIG. 1;
FIG. 5 is a right-side view of the vehicle mount of FIG. 1;
FIG. 6 is a top plan view of the vehicle mount of FIG. 1;
FIG. 7 is a bottom plan view of the vehicle mount of FIG. 1;
and,
FIG. 8 is a perspective view of the vehicle mount of FIG. 1 in
which a mobile phone is shown in broken lines to illustrate an
example of how the mobile phone may be docketed to the
vehicle mount. The broken lines showing the mobile phone is
for illustrative purpose only and form no part of the claimed
design.
